Fig. 4

Fig. 7

Fig. 6

FIGURE 1 is a front, top and right side perspective view of an insulator housing for electrical contacts showing our new design;

FIGURE 2 is a front elevational view thereof;

FIGURE 3 is a bottom plan view thereof;

FIGURE 4 is a rear elevational view thereof;

FIGURE 5 is a top plan view thereof;

FIGURE 6 is a right side elevational view thereof; and

FIGURE 7 is a left side elevational view thereof.

We claim:

The ornamental design for insulator housing for electrical contacts, substantially as shown.
